UNITED STATES PATENT OFFICE.

PAUL PRAETORIUS, OF STETTIN, GERMANY.

STARTING AND REVERSING DEVICE FOR MARINE INTERNAL-COMBUSTION ENGINES.

1,165,539.

Specification of Letters Patent. Patented Dec. 28, 1915.

Application filed June 8, 1910. Serial No. 565,870.

To all whom it may concern:

Be it known that I, PAUL PRAETORIUS, a subject of the Emperor of Germany, residing at Stettin, Germany, have invented certain new and useful Improvements in Starting and Reversing Devices for Marine Internal-Combustion Engines, of which the following is a specification.

The present invention relates to marine engines, such as internal combustion engines of the "Diesel" motor type, and more particularly refers to the combination with such a motor of a pair of starting and reversing turbine rotors, one for going ahead 15 and the other for going in the reverse direction.

In the accompanying drawing is shown a diagrammatic side elevation, partly in section of the improved "Diesel" motor forming the subject matter of the present invention.

As shown in the drawing, the Diesel motor A, by its main shaft C, is connected with a starting and reversing turbine B having two rotors *a* and *b* rigidly mounted on the shaft C within a casing *n*. The rotor *a* in coöperation with the guide blade segment *c* forms the ahead turbine and the rotor *b* in coöperation with the guide blade segment *d* 25 the astern turbine. The rotors *a* and *b* act at the same time as substitute for a fly-wheel.

The medium required for the starting or reversing, for example air under pressure, is compressed in the compressor D and led 35 through a pipe *o* to a reservoir E from which connection is established through the pipes *p* *q* *e* and *p* *r* *g* to the nozzles *f* or *h* respectively. These connections may be controlled by a suitable valve *s* operated by 40 a hand lever *t*. The medium having produced its effect can escape through an opening *i* of the casing *n* or be carried away through a pipe connected therewith.

To increase the efficiency of the turbine device a part or all of the exhaust gases of the turbine rotors is passed through a jacket 45 provided in the casing *n* and surrounding the turbine rotors, and allowed to escape through an exhaust connecting branch *m*.

If the "Diesel" motor is to be started or reversed for "ahead" travel, connection is 50 established between the inlet connecting

branch *e* and the reservoir E. Compressed air (gas or steam) flows then through the nozzle *f* into the casing *n* and causes the 55 rotor *a* and the motor shaft C to be rotated for the forward travel.

If it is desired to start or reverse the "Diesel" motor "astern," the inlet connecting branch *g* is brought in connection with the 60 reservoir E, so that the driving medium flows in the casing *n* through the nozzle *h* and thereby rotates the rotor *b* and the motor shaft C for the rearward travel.

As soon as the "Diesel" motor is started 65 or reversed in the desired direction, that is to say, as soon as ignition has taken place in the working cylinders of the "Diesel" motor and the latter is beginning to run of its own power, the supply of the driving medium to 70 the rotor *a* or *b* respectively is disconnected, the two rotors, however, remain running and act as fly-wheels.

The above described combination meets all reasonable requirements. The starting 75 or reversing of the "Diesel" motor by rotation will make that its working parts are not subject to wear from shocks as is the case with other starting or reversing methods. The fact that all controlling 80 parts for starting the motor are done away with for each working cylinder, makes that the number of valves, cams, levers and other required controlling elements is considerably lessened. Hence less possible injury 85 and less cost of repairs. As contrary to what happens in other systems, no expanding cold air can enter the working cylinders, the motor can be started and reversed with all safety even when the temperature is 90 low. The material of the working cylinders and pistons does not suffer from differences of temperature, caused by hot working gases and cold air. Experiments have taught that by the improved means a powerful 95 torque is produced with a comparatively small consumption of compressed air.

I claim—

In a marine engine, the combination of an internal combustion engine of the Diesel 100 motor type; a motor shaft adapted to be driven by the said engine in either one direction or the other; a pair of turbine rotors rigidly mounted on the said motor shaft;

and means for at will directing fluid under pressure to either of said rotors in respectively opposite directions, one rotor forming the ahead turbine and the other rotor forming the astern turbine for starting or reversing the engine.

5 In testimony whereof I have signed my

name to this specification in the presence of two subscribing witnesses.

DR. PAUL PRAETORIUS.
